UNITED STATES PATENT OFFICE.

EDWARD WILLIAM WAGNER, OF CHEROKEE, CALIFORNIA.

KEY-FASTENER.

SPECIFICATION forming part of Letters Patent No. 291,434, dated January 1, 1884.

Application filed October 20, 1883. (No model.)

To all whom it may concern:

Be it known that I, EDWARD W. WAGNER, of Cherokee, in the county of Butte and State of California, have invented an Improvement 5 in Key-Fasteners; and I hereby declare the following to be a full, clear, and exact description thereof.

My invention relates to a new and useful key-fastener, the object of which is to secure 10 the key within the lock, in order to prevent it from being turned from the outside by any of those means known to and in use by those who seek unlawful entrance.

My invention consists in a sliding bolt seated 15 within the lock-casing, and operated by means of a thumb-piece projecting through a slot in said casing, said bolt being adapted to engage with a notch in the bit of the key, as I shall hereinafter fully explain by reference to the accompanying drawings.

Figure 1 is a side elevation of a lock, showing 20 the key fastened by my device. Fig. 2 is a vertical transverse section of a lock with the bolt C in elevation and in engagement with 25 the bit of the key. Fig. 3 is a view of the interior of a lock, showing how the bolt C engages with the bit of the key.

A is the casing of a common flat lock, having 30 the hole a for the handle or knob, the key-hole b, and the lock-bolt c.

It is unnecessary to describe the mechanism 35 of the lock, as this may be of any suitable form. In the casing, just in front of the key-hole, is made an elongated slot, B. A bolt, C, lies within the casing just behind the slot, and has a thumb-piece, D, extending through it, whereby said bolt may be operated. The lower edge of this bolt rests upon the bottom 40 of the casing as a guide, though I may seat it in any manner I find best.

K is the key, having a bit, k, in which any suitable slits or cuts may be filed, to adapt it to the particular description of lock used; but on its inner side is made a large notch, m,

adapted to receive the end of bolt C. When 45 the key is inserted and turned to shoot the lock-bolt, it must be turned far enough to allow its bit to project downwardly, in which position the bolt C may be slid to cause its end to engage with the notch m in the bit. 50 When thus adjusted, the key cannot be turned from the outside or pushed out. To release it the bolt is drawn back.

I am aware that devices are known for this 55 purpose which embody a sliding bolt adapted to engage with the key in some manner, to prevent its turning; but in these the bolt is seated on the outside of the lock or on the escutcheon of the key-hole, in guides especially prepared for it, and it engages with the key 60 stem or shank. In addition to the extra work necessary upon these devices to make them operative, they are in the way, and do not look well, besides not being very secure, by 65 engaging with the stem of the key; but in my device everything but the small thumb-piece is out of sight, and may therefore be made as cheaply as possible, besides being out of the way, and having a surer engagement with the bit than with the stem of the key. I do not 70 therefore claim, broadly, a sliding bolt engaging with a key; but

What I do claim as new, and desire to secure by Letters Patent, is—

The lock-casing A, having a slot, and the bolt 75 C within said casing, and having a thumb-piece projecting through said slot to the outside, in combination with the key K, having bit k, with a notch, m, with which said bolt is adapted to engage to prevent the key from turning, 80 substantially as herein described.

In witness whereof I have hereunto set my hand.

EDWARD WILLIAM WAGNER.
